ELECTRODE MOUNTING DEVICE

Philip Giuffrida, Lawrence, Mass., assignor to
 Combustion Control Corporation, Cambridge,
 Mass., a corporation of Massachusetts

Application June 8, 1948, Serial No. 31,659

12 Claims. (Cl. 174—52)

1 This invention relates to apparatus for mounting a flame detection electrode on a furnace. Automatic and semi-automatic furnaces, burning volatile fuels are generally equipped with a flame failure safeguard which operates to shut off the fuel supply, and so prevent explosion, if the burner fails to ignite properly or if the flame accidentally becomes extinguished. One type of flame failure control employs as a detecting element an electrode, or flame rod, which establishes an electrical contact with the flame, thus completing an electrical circuit which operates in connection with associated electrical apparatus to control the fuel supply. The electrode is held in an insulating mounting on the furnace wall. Because of the serious hazards involved, especially in burners of the large industrial types, the reliability of the flame failure device is of utmost importance. The flame rod type of detector and its insulator are necessarily exposed to the combustion chamber and eventually accumulate a deposit of soot. Safe operation of the flame failure control can be insured by so designing the circuit that excessive loss of resistance between the flame rod and ground, due to soot deposit on the insulation, is equivalent to flame failure and results in a shut-down. The control then prevents operation of the burner until the flame rod insulation is cleaned. Such a circuit is described, for example in co-pending application to E. C. Thomas, Serial No. 754,435, filed June 13, 1947, Flame Failure Safeguard. Since such a shut-down may occasion considerable inconvenience and expense, however, it is desirable to delay the accumulation of soot and prolong the satisfactory operation of the flame rod as much as possible. The rod must also be protected against short circuiting or accidental contacts which might, under certain conditions, maintain operation of the fuel supply in the absence of flame. It may also be advantageous in some installations to mount certain electrical components of the control circuit such as an amplifier tube, as close to the flame electrode as possible, in which case, the component must be protected against excessive heat.

The object of this invention is, accordingly, to provide an electrode mounting device which protects the flame electrode from accidental contact, which maintains adequate insulating between the electrode and the furnace wall over long periods of operation, which may house an amplifier tube and other electrical components associated with the flame rod circuit, which permits ready access for cleaning and inspecting, and which is simple, durable, compact, and easily installed.

These and other advantages and novel features of the mounting device will be more readily understood from the following description. In the accompanying drawings:

2 Fig. 1 is a side elevation of the device; Fig. 2 is a partial cross-section along lines 2—2 of Fig. 1;

Fig. 3 is a view along lines 3—3 of Figs. 2 and 4; Fig. 4 is a plan view of the device with the housing cover removed;

Fig. 5 is a partial cross-section along lines 2—2 of Fig. 1 showing the interior of the housing arranged for mounting on amplifier tube.

As illustrated in Figs. 1, 2 and 4, a housing consisting of base 10 and cover 11 is secured to a mounting flange 18 by three screws 19 which extend through spacers 17 and are threaded into bosses 16. The mounting flange 18 is provided with a recess 22 which slides over a piece of pipe 23, the other end of which is welded into the wall of the furnace (not shown) in which the flame electrode is to be mounted. Flange 18 is prevented from turning on the pipe 23 by set screws 7. Cover 11 is secured to base 10 by screws 50. A gasket 15 is ordinarily provided between lips 13 and 14 of cover 11 and base 10 respectively. The flame rod assembly is secured to the vertical inner face of base 10 by screws 32 which extend through insulating spacers 36, 37, 38 into tapped holes in the housing. A guard plate 34 is secured by rivets 49 to spacer 38. Mounted on either side of plate 34, and separated from it by compressible gaskets 51 are ceramic insulators 27 and 28. A boss 54 on insulator 28 extends into recess 55 in insulator 27. A stud 43, of brass or other metal of good conductivity, extends through insulators 27 and 28. On its inner threaded end, stud 43 carries sealing washer 52, contact bracket 39, lock washer 56, nut 48, contact lug 42, and nut 47. Mounted on the outer threaded end of stud 43 are sealing washer 43, baffle plate 33, lock washer 57 and chuck 20. In assembling the insulators and other parts onto the rod, a heat resistant cement is preferably applied between adjoining faces. When nut 48 is tightened, the entire assembly is held securely on guard plate 34. Nut 47 may be removed and replaced as required for wiring purposes.

The outer end of chuck 20 is recessed to receive the flame rod 21, which is a piece of rod of conductive material such as nickel steel cut to any required length. The rod is secured by set screw 29. A fin 26 is inserted between bosses 16 and spacers 17 to dissipate the heat conducted through pipe 23 and flange 18 from the furnace wall. Between the housing and the mounting flange, the rod assembly is surrounded by a heat resistant glass shield 58. The inner end of the shield rests against gasket 59, held in place by boss 61 on the housing, and the outer end presses against gasket 60 mounted in recess 64 in the flange. The shield protects the rod assembly, between the housing and the mounting flange, from dirt, accidental contact, and tampering, and, at the same time, permits visual inspection

of the insulation. Flange 18 is thickened on its underside to accommodate clean-out hole 25 to which an air hose may be applied for blowing soot off the flame rod insulation. Where required, an air hose may be permanently attached for cooling. When the hole is not in use it is closed by plug 24.

It will be noted that the insulation of the flame rod does not touch any part of the housing but is in contact only with guard plate 34. Consequently any leakage current due to soot, dirt or moisture deposits on the surface of the insulation will flow between the rod and guard plate rather than the rod and ground. In order to minimize such leakage, the insulators 27 and 28 are so constructed as to provide long internal and external surface paths between the rod and the guard plate and the more exposed insulator 27 is protected against blow-backs of soot by baffle 33. In the control circuit illustrated in the copending application to E. C. Thomson, previously referred to, the guard plate is so connected that either excessive leakage, or short circuit, between the rod and the guard ring will cause the burner to shut-down as on flame failure. Provision is made in this device for employing this circuit characteristic to shut down the burner when the cover 11 is removed, so that the burner cannot be maintained in operation, or started by accidental contact between the inner end of the rod and some external conductive object, when the cover is off. For this purpose, a leaf spring 46 is riveted to the guard plate. The spring projects through slot 68 in contact bracket 39 and carries, on its free end, insulating button 44 fastened by screw 45. When cover 11 is in place, it presses against button 44 and pushes spring 46 out of contact with bracket 39. When the cover is removed, spring 46 engages bracket 39, and thus short circuits the guard plate to the flame rod. In Fig. 2, wire 61 of cable 62 is connected to the rod by terminal washer 42. The guard plate terminates in a bracket 69, to which the shield 66 of cable 62 is fastened by cable clamp 40. The cable runs through a conventional connector 31 mounted in one of the holes 30.

Fig. 5 shows the housing adapted for mounting amplifier tube 74, and other electrical components of suitable size. A chassis 73 is secured to housing base 10 by screws 75 and 76. A terminal board 70 is supported by chassis 73 and straps 71 which are secured to the upper pair of screws 32 and clear guard ring 34 and button 44. Nut 47 and lug 42 are omitted. Bracket 39 is provided with an extension 65 to which internal wiring connections to the rod are made. A flat guard plate 34 is used. In other respects, the embodiment of Fig. 5 is the same as that of Fig. 2.

Since certain changes may be made in the above-described article and different embodiments of the invention could be made without departing from the scope thereof, it is intended that all matter contained in the above description or shown in the accompanying drawings shall be interpreted as illustrative only and not in a limiting sense.

What is claimed:

1. An electrode mounting device comprising: a housing; a mounting flange connected to, but spaced from, said housing; an insulating spacer attached to said housing; a conductive plate

mounted on said insulating spacer; a pair of insulating bushings, mounted one on either side of said plate and spaced away from, and out of contact with, said spacer and said housing; a conductive rod extending through said bushings; and means on said rod for clamping said bushings together against said plate thereby supporting the entire rod and bushing assembly on said plate.

2. A device according to claim 1 having a transparent shield surrounding said bushings and said rod in the space between said housing and said flange.

3. A device according to claim 2 having a cooling fin mounted between said housing and said flange.

4. A device according to claim 2 having a baffle plate mounted near the outer end of said rod extending toward, but spaced from, said shield.

5. A device according to claim 1 having a removable housing cover and a switch which connects said rod to said plate when said cover is removed.

6. A device according to claim 5 having a transparent shield surrounding said bushings and said rod in the space between said housing and said flange.

7. A device according to claim 5 wherein said switch comprises: a leaf spring attached to said plate, and carrying on its free end an insulating button adapted to engage said cover; and a contact lug connected to said rod.

8. A device according to claim 1 wherein one of said bushings is centrally recessed, and the other bushing carries a boss which extends into said recess.

9. A device according to claim 8 having a removable housing cover and a switch which connects said rod to said plate when said cover is removed.

10. A device according to claim 8 having a transparent shield surrounding said bushings and said rod in the space between said housing and said flange.

11. An electrode mounting device comprising: a housing; an insulating spacer attached to said housing; a conductive plate mounted on said spacer; a pair of elongated insulating bushings, mounted one on either side of said plate and spaced away from and out of contact with, said spacer and said housing, one of said bushings being centrally recessed and the other bushing carrying a boss which extends into, but is spaced from the walls of, the recess; a conductive rod extending through said bushings; and means carried by said rod for clamping said bushings together against said plate thereby supporting the entire rod and bushing assembly on said plate.

12. A device according to claim 11 wherein the inner surface of said bushings is spaced from the outer surface of said rod.

PHILIP GIUFFRIDA.
